UNITED STATES PATENT OFFICE.

CHARLES F. GESCHICKTER, OF WASHINGTON, DISTRICT OF COLUMBIA.

WINDOW SCREEN.

Application filed February 12, 1924. Serial No. 692,414.

To all whom it may concern:

Be it known that I, CHARLES F. GESCHICKTER, a citizen of the United States of America, residing at Washington, in the District of Columbia, have invented certain new and useful Improvements in Window Screens, of which the following is a specification.

The average window screen is mounted upon a window slide fastened to the window frame. This construction is objectionable in that the wood at the sliding joint swells due to moisture in the air thus making it almost impossible to raise the screen at times, then again the wood shrinks which results in an extremely loose interengagement of the sliding joint which makes it possible for the screen to become accidentally dislodged and fall out. Another objection to this type of screen is that in order to remove or replace the screen it is necessary to raise it bodily upon the top edge of the slide member.

The object of my invention is to provide a screen with a sliding joint of such construction that the screen may be introduced and engage with its slideway at any point between the top and bottom of the slideway.

A further object of my invention is to provide a joint between the slideway and slide which will not be affected by atmospheric conditions.

With these objects in view my invention consists of the parts and combination of parts as will be hereinafter more fully described.

In the drawings:

Figure 1 is a front elevation of a window screen embodying my invention, one of the side stiles being in section.

Figure 2 is a transverse detail section of a window frame equipped with my screen.

Figure 3 is an enlarged detail sectional view of the operating member.

Figure 4 is a transverse sectional view of Figure 3.

Figure 5 is a detail sectional view of a modified embodiment.

Figure 6 is an elevation detail view of the inner face of the side stile.

Figure 7 is a detail view of another embodiment of my invention.

The reference numeral 1 designates a window frame of any approved construction having stop beads 2, 3 and 4. To the stop bead 2 which may be either the outside stop

bead or the inside stop bead of a window frame is secured a metal channel slideway 5.

My improved screen comprises a frame 6 having any desired kind of wire cloth secured therein. The side stiles of the screen are provided with recesses 7, which extend entirely through the stiles from side to side. In these recesses, I securely attach one end of the spring 8, the free end of the spring having a pair of standards 9 depending therefrom, between which is journalled a revolvable slide 10.

An operating block 11 is slidably mounted in the recesses 7 and is provided with a cam face 12 which is adapted to engage the spring 8, said block being provided with an operating handle 13, which handle extends through a slot 14 of the face plate 15. In the preferred construction the cam block 11 is provided with a lug 16 which projects through the slot 14 of the plate 15 and is held in said slot by being riveted to a plate 17 which slides on the outer face of the plate 15, the handle 13 being formed by bending up one end of the plate 17.

In the operation of the device the wheels, or revolving slides 10, are all pulled into the recesses 7 and consequently do not project beyond the outer edge face of the side stiles as illustrated in the drawings, the spring 8 pulling the wheels 10 to this position. Now, when the screen frame has been introduced between the slideways 5 the cam blocks 11 are pulled downward by means of the handles 13 whereupon the cam face 12 engages the spring 8 and forces it outwardly toward the slideway 5, and consequently forces the wheels 10 into the slideway 5 in which position the wheels are held in full interengaging position with the slideways 5 so long as the cam block remains in its lowered position. When the cam block is pushed down to its lowermost position it is held in that position by gravity and it also has a slide binding action on the underface of the plate 15 by reason of the fact that the spring 8 is exerting its power toward the under face of the plate 15.

From the above it will be seen that the screen embodying my invention can be engaged or disengaged with its slideways at any point between the top and bottom of the slideways.

In Figure 5 I have illustrated another embodiment of my invention in which I mount the slide wheel 10, its associated

spring 8 and operating cam 11 in a self contained housing 20 so that the invention may be sold as an article of manufacture in stores.

5 In Figure 7 I have illustrated the slide as a pin 21 which may be secured to the spring 8 and perform the same function as the wheel 10.

10 It will, of course, be understood that changes may be made in the details of construction herein shown, within the scope of the appended claim without departing from the spirit of my invention.

What I claim is:

15 The combination with a screen frame having a pair of slots in each side stile, of an attachment to be placed in each of said slots,

said attachment comprising a housing having a slot in each of its side walls, a leaf spring within the housing and secured at 20 one end to the housing, depending flanges at the free end of the spring, a roller secured between said flanges, said spring normally holding the roller within the housing, said roller being adapted to be projected through one of said slots of the housing, a cam slidably mounted in the other of the slots of the housing and adapted to slidably engage the said spring and project the said roller through one of the slots of the housing. 25

30 In testimony whereof I affix my signature.

CHARLES F. GESCHICKTER.
